JOSIAH DOW, OF PHILADELPHIA, PENNSYLVANIA.

GENERATION OF PRESSURE.

1,237,877.

Specification of Letters Patent. Patented Aug. 21, 1917.

Application filed March 27, 1916. Serial No. 86,955.

To all whom it may concern:

Be it known that I, JOSIAH Dow, a citizen of the United States, and residing in the city of Philadelphia, county of Philadelphia, in the State of Pennsylvania, have invented certain new and useful Improvements in Generation of Pressure, of which the following is a specification, reference being had to the accompanying drawings, forming a part hereof.

This invention relates to the generation of pressure by the direct combustion of a combustible fluid within the pressure generating chamber, from which the vapor under pressure may be conducted to a motor or other place of use where it may be used expansively. In accordance with the invention the combustible fluid (preferably alcohol, with reference to the use of which the invention has been developed), being supplied under pressure and preferably first vaporized, when the operation has once been instituted, by the heat developed by its own combustion, is delivered, in the form of vapor, into a mixing chamber where it is mixed with the proper amount of air (also supplied under pressure) to maintain perfect combustion, and thence into a combustion chamber where it is burned, and the products of combustion, preferably after reheating or superheating by the heat developed and greatly expanded by comparison with the original volume of alcohol vapor and air, are conducted to a motor in which the energy developed by heat is expended in useful work. The apparatus in which the operation is carried on is not in an ordinary sense a steam generator although the alcohol in combustion develops both water vapor and carbonic acid gas, but the excess of heat developed above that necessary for the development of pressure which can be used advantageously, may be utilized economically in the vaporization of a small additional quantity of water, which is admitted also under pressure and preferably in the form of vapor, whereby not only is the excess of heat absorbed but some additional volume of vapor under pressure is created. Preferably the quantity of water or of steam admitted is regulated automatically by the varying temperature so that the resultant pressure is substantially uniform. The invention will be more fully described hereinafter with reference to the

accompanying drawings in which it is illustrated and in which,

Figure 1 is a view in vertical central section of an approved form of the generator.

Fig. 2 is a view of the same in horizontal section on the plane indicated by the broken line 2—2 of Fig. 1.

Fig. 3 is a diagrammatic view showing the generator in its relation to the devices for supplying air, alcohol and water under pressure.

Fig. 4 is a detail top view of a portion of the generator illustrating particularly the automatic control of the water.

In the mechanical embodiment of the invention illustrated in the drawings there are combined an outer shell or cylinder *a*, provided with heavy heads *b* and *c* and an inner, concentric cylinder or shell *d*, provided with headers or diaphragms *e* and *f*. There may be also an inclosing shell or casing *g*, the space between the outer shell *a* and the casing *g* being packed with asbestos or some other suitable non-conductor. The alcohol is supplied under pressure from a suitable source through a pipe *h* which is preferably coiled with several turns around the shell *a*, so that the alcohol may be vaporized by the heat, and is then connected to a suitable nozzle *h'* formed in the lower head *c*. The air which is to support the combustion of the alcohol is also supplied from a suitable source under pressure through a pipe *i* to an air inlet *i'* in the lower head *c*, the alcohol vapor nozzle *h'* being preferably located in the throat of the air inlet *i'*, in the relation of an atomizing nozzle, so that the alcohol vapor and air shall be thoroughly atomized and mixed. A perforated diaphragm or plate *c'* is preferably located between the inlet *i'* and the main combustion chamber to effect a thorough distribution and intimate mixture of the air and alcohol vapor, the mixing chamber being formed on one side of such diaphragm while the combustion chamber is formed on the other side thereof.

An igniter *k* of any suitable character, shown as an ordinary spark plug, is provided for the purpose of instituting combustion at the outset.

Tubes *l* are secured in the headers or diaphragms *e* and *f* and conduct the products of combustion from the chamber *f'* below the header *f* to the chamber *e'* above the

2
header e and from the latter chamber the products of combustion are conducted through passage e^2 to the annular chamber a' between the shell a and the shell d . From such annular chamber they are conducted through passages d' to the interior of the shell d , among the tubes l , whereby they are reheated or superheated, and from the chamber d^2 within the shell d they are conducted 10 by a suitable pipe d^3 to the motor or other place of use.

The water is supplied under pressure from a suitable source through a pipe m which is coiled with several turns within the annular chamber a' so that the water may be vaporized in the pipe m and may pass through its lower end and through perforations m' in the lower coil of the pipe into the lower portion of the annular chamber a' to mingle 15 therein with the products of combustion and to be delivered with such products of combustion through the passages d' into the chamber d^2 .

Since the chief purpose of the water or steam admitted to the combustion chamber is to absorb and to be vaporized by the excess of heat, it is desirable that the admission of the water or steam should be regulated in accordance with the variation of 20 heat within the generator. Accordingly there is provided in the upper part of the generator, as at n , (see Figs. 1 and 4), a pyrometer rod which, through suitable mechanical devices, indicated at n' , is made to 25 control a balanced valve at m^2 in the water supply pipe m so that as the heat in the generator increases above the predetermined normal more water shall be admitted and vice versa.

40 A safety valve may be secured to the upper head e , as indicated at o in Figs. 1 and 3.

It will be obvious that any suitable means may be provided for supplying the alcohol, the air and the water under pressure. It is 45 desirable that these fluids be supplied under substantially the same pressure, which shall be uniform, and for that purpose there may be employed such means as are indicated somewhat diagrammatically in Fig. 3. Air

50 from a pump operated by hand, or, by any other suitable source of power, after the generation of power is instituted, by the motor itself, is admitted under the required pressure, preferably about 180 pounds, through 55 a pipe p to one end of a cylinder p' . From the same end of the cylinder air may pass through a pipe p^2 to the pipe i before mentioned. A branch p^3 from the pipe p^2 conducts the air under pressure to the top of 60 the vessel q containing water to deliver the water under pressure to the pipe m by which it is conducted to the generator.

Within the cylinder p' is a piston p^4 (preferably a double piston, as shown), and, in 65 the opposite end portion of the cylinder p'

is placed the alcohol or other combustible fluid which may therefore be delivered under substantially the same pressure as the air and the water directly to the generator through the pipe h .

70

In order that the apparatus may be automatic in its operation the admission of the several elements, that is, the alcohol or other combustible fluid, the air and the water, may be regulated by the pressure developed in 75 the generator. For this purpose there may be placed in the pipes h , i and m suitable regulating valves, as at h^4 , i^4 and m^4 , of suitable construction, by which the admission of the alcohol, air and water shall be 80 regulated, such valves being in turn subject to and controlled by variations of pressure 85 in the generator through pipes h^2 , i^2 and m^2 .

80

It will be understood that the efficiency 85 of the generator in the development of power depends upon the expansion in the generator, through combustion, of the elements which enter into the combustion, namely, the alcohol, the air, and the water vapor, if 90 water vapor be admitted, and that the efficiency of the motor in which the products of combustion are used will depend upon the extent to which that largely increased volume at the same pressure may be made to 95 yield its energy to the motor in a reduction 100 to normal pressure. It is believed that the highest efficiency of the generator can be secured with a construction such as that illustrated in the drawings and with the addition of water vapor, largely because of 105 its efficiency in the transmission of heat, but it will be seen that some degree of efficiency might be attained without the use of water vapor and without the internal tubes for 110 vaporizing the alcohol and the water and for reheating the products of combustion shown in the drawings. Various other changes in details of construction and arrangement will readily suggest themselves to meet different conditions of use, and it 115 will be understood that the invention is not restricted to the particular construction shown and described herein except as set forth in the appended claims.

115

I claim as my invention:

1. As an improvement in the art of generating pressure from a combustible fluid, the mode herein described which consists in delivering to a combustion chamber under pressure a mixture of combustible fluid and air, directing the products of combustion first forwardly, then rearwardly, and then again forwardly, and during their second forward excursion subjecting them to the action of the products of combustion during their first forward excursion, and adding water to the products of combustion at an intermediate stage of their travel.

120

2. As an improvement in the art of generating pressure from a combustible fluid, the

125

130

mode herein described which consists in delivering to a combustion chamber under pressure a mixture of combustible fluid and air, directing the products of combustion first forwardly, then rearwardly, and then again forwardly, and during the second forward excursion subjecting them to the action of the products of combustion during their first forward excursion, and adding to the products of combustion at an intermediate point in their travel water in volume only sufficient to prevent excessive heating of said products of combustion during their second forward excursion.

15. 3. In apparatus for generating pressure from combustible fluid, the combination of a shell having opposite headers or diaphragms, a chamber within said shell, tubes crossing said chamber and secured in said headers, 20 a casing inclosing a chamber in advance of said tubes, means for supplying to said chamber, under pressure, a mixture of combustible fluid and air, means for conducting the products of combustion from the tubes 25 to the chamber surrounding the same, means for mixing water with said products of combustion as they enter said chamber, and means for conducting the reheated products of combustion from said chamber to the place of use.

30. 4. In apparatus for generating pressure from combustible fluid, the combination of a shell having opposite headers or diaphragms, a chamber within said shell, tubes crossing said chamber and secured in said headers, 35 a casing inclosing a chamber in advance of said tubes, means for supplying to said chamber, under pressure, a mixture of combustible fluid and air, means for conducting the products of combustion from the discharge ends of the tubes to the chamber containing the same, said points of entry being adjacent to the receiving ends of the tubes, means for mixing water with said 40 products of combustion at the point where they enter said chamber, and means for conducting the reheated products of combustion from said chamber to the place of use.

45. 5. In apparatus for generating pressure from combustible fluid, the combination of inner and outer shells each provided with headers at its opposite ends, said shells and headers being so disposed as to form a chamber within the inner shell, an annular cham-

ber between the shells and chambers between 55 the headers at the opposite ends thereof, tubes secured to the headers of the inner shell, and providing communication between the opposite end chambers, means for supplying to one end chamber, under pressure, 60 a mixture of combustible fluid and air, means for conveying products of combustion from the other end chamber to the annular chamber between the shells, and thence to the chamber surrounding the tubes, means for 65 mixing water with said products of combustion during such passage, and means for conveying the reheated products of combustion from the last named chamber to the place of use.

70. 6. In apparatus for generating pressure from combustible fluid, the combination of inner and outer shells each having headers at opposite ends, said shells and headers being so disposed as to form a chamber within 75 the inner shell, an annular chamber between the shells and chambers between the headers at the opposite ends thereof, tubes crossing said inner chamber and secured to the headers thereof, means for supplying to one of 80 said end chambers, under pressure, a mixture of combustible fluid and air, means for conveying products of combustion from the opposite end chamber to the annular chamber between the shells and thence to the chamber 85 surrounding the tubes, a water heater contained in said annular chamber, means for discharging water from said heater into the products of combustion as they enter the chamber surrounding the tubes, and means 90 for conveying the reheated products of combustion from said chamber to the place of use.

75. 7. In apparatus for generating pressure from combustible fluid, the combination of a shell structure having at each end inner and outer headers with chambers between them, tubes secured to the inner headers and connecting said end chambers, a perforated diaphragm extending across one end chamber 100 between the inner and outer headers, and means for conveying, under pressure, to said chamber, on the outer side of the diaphragm, a mixture of combustible fluid and air.

105. This specification signed this 24th day of March A. D. 1916.
